REVERSIBLE ROTARY BOLT LOCK

Waldemar A. Emmer, Long Beach, Calif.

Application November 27, 1943, Serial No. 511,933

8 Claims. (CL 292—344)

This invention has to do with lock or latch mechanisms of the rotary bolt type, and is concerned particularly with improvements in the bolt element itself and in the combination of the bolt and its keeper, whereby it is now made possible to attain many advantages and results not capable of accomplishment by conventional rotary bolt latch mechanisms.

Rotary bolts of this general type commonly comprise a plurality of radially extending, equi-angularly spaced teeth or heads engageable by the bolt actuating mechanism or cam means, and engageable also with a keeper. Frequently the bolt is designed to have inner and outer portions engageable respectively by the cam means and keeper, the radially extending heads of such portions either being slired or angularly offset, for purposes known to those familiar with the art. Heretofore, the individual bolt heads have been shaped to form corresponding side surfaces of curvature suitable for engagement by the cam means or keeper, as the case may be. Such side surfaces, however, have had no particular shape relationship to the opposite side surfaces of the heads, and individually, the heads have been unsymmetrical. For this reason, as well as others, depending upon particular types and forms of latch bolts, it has been necessary to make individually shaped bolts for left-hand and right-hand latch mechanisms, and in either type it has been necessary to position the bolt in only one end relationship in the mechanism. In other words, bolts otherwise of the same size have not been interchangeable in left-hand and right-hand locks, nor has the bolt been reversible (in end position) in either individual type of mechanism.

One major object of the invention is to provide an improved form of latch bolt characterized by its adaptability for use in either right-hand or left-hand latch mechanisms, and by its adaptability for reversal in any single mechanism. Briefly, this object is accomplished by giving the bolt features of symmetry permitting the cam mechanism and keeper to have the same action and effect against either side surfaces of the bolt heads. This purpose is further served in bolts having angularly offset cam-engaging and keeper-engaging ends, by offsetting one set of heads equi-angularly with respect to the other, all as will later appear.

The invention contemplates further improvements in the particular shape characteristics of the side surfaces of the bolt heads, and in the

combination of the bolt shape and the shape of a bolt-engaged surface of the keeper. My objects in these respects are to accomplish more efficient timing of the operation of the cam mechanism with relation to the bolt travel along the keeper, and to provide greater assurance than heretofore has been possible, against improper operation or timing of the cam action, due to variations in certain relative positions of the parts that may be expected to occur in practical installations and uses of the mechanism.

The particular manners in which the above stated features and objects of the invention are accomplished, will be more readily understood 15 from the following description of certain typical and illustrative embodiments of the invention. Reference is had throughout the description to the accompanying drawings in which:

Fig. 1 is an elevational view of the lock case, rotary bolt and associated parts;

Fig. 2 is a section on line 2—2 of Fig. 1;

Fig. 3 is a section on line 3—3 of Fig. 2;

Fig. 4 is an enlarged end view of the rotary bolt;

25 Figs. 5 through 10 are diagrammatic views illustrating sequential relative positions of the rotary bolt and keeper within the complete range of latching rotation of the bolt;

Fig. 11 is an elevation showing a variational form of the invention;

Fig. 12 is a section on line 12—12 of Fig. 11; and

Fig. 13 is a cross-section on line 13—13 of Fig. 11.

Referring first to Figs. 1 to 3, the mechanism may be described generally as comprising a rotary bolt 16 and bolt-actuating cam means 11, both supported by side 12 of the case 13, and a mechanism 14 for releasing the camming means and carried at the inside of portion 15 of the case. The rotary bolt 16 may be regarded as having a keeper-engaging end 16 at the outside of wall 12 of the case, and a cam engaged end 17 at the inside thereof, these end portions being separated by a circular flange 18 received within an opening 19 in the case. The bolt is rotatable on a pivot or pin 20 having its inner end supported at 21 in a plate 22 integral with the case 13. The outer end of the pin 20 terminates at 23 in the usual semi-housing or bracket 24.

As best illustrated in Fig. 4, each of the end portions 16 and 17 of the bolt is shaped to provide a plurality of radially extending, equi-angularly spaced teeth or heads 25, four being

shown as typical. In the broad aspects of the invention, the heads of the two end portions 16 and 17 of the bolt may be aligned, or angularly offset for the known purpose of better adapting the position of the camming means with relation to the bolt for more convenient and compact arrangement of the parts within the case. Here the heads 25 of the cam-engaged end 11 of the bolt, are shown to be offset equi-angularly, or at 45 degrees, with relation to the heads of the keeper-engaging end 16 of the bolt. It will be observed that all the side surfaces of all the heads 25 have the same shape, and that the opposite side surfaces of each head are symmetrical with relation to the radial center line (e. g. line L—L') of the head. As previously indicated, this feature is of importance in many respects, among which is the practical advantage of enabling a single bolt, thus shaped and designed, to be capable of installation and use in either a left-hand or right-hand latch. Moreover, the position of the bolt may be reversed in either individual type of latch, since by virtue of their symmetrical shape and angular positions, the heads of the end portions 16 and 17 have the same relationship in reversed positions in the case. Thus for all latching mechanisms employing the same size rotary bolt, it is only necessary to make one form of bolt which may be installed without regard to any particular end relationship to the rest of the mechanism.

With further reference to the particular shape characteristics of the bolt, it will be observed that each side face of each of the heads 25 has an intermediate recess or inwardly curved portion adapted to receive a curved surface of the keeper, as later explained. Referring to Fig. 4, the shape of each side face 26 is one of reverse curvature, the outer end portion 27 of the surface being curved outwardly, and the intermediate portion 28 curving reversely and inwardly to the angular center line A—A' between adjacent teeth. The adjacent curved surfaces 28 of adjacent heads 25 preferably are described by an arc, substantially as illustrated, having its center on the angular center line A—A'.

Any suitable means engageable with the inner end portion 17 of the bolt may be employed to urge the bolt in a latching direction. As illustrative, such means is shown to comprise a usual arrangement of one or more cams 29 and 30 pivotally supported on a shaft 31, the inner end of which terminates at 32 within plate 22, as shown in Fig. 2. The outer end of the shaft terminates at 33 within the usual type of keeper-engaging lug 34 formed integrally with the case flange 12. Cams 29 and 30 have the usual length relationship, one being longer than the other, so as to successively engage and rotate the bolt in a latching direction throughout a predetermined range of movement. If desired, I may also provide for operation in conjunction with the cams, a holding element 35 also pivotally movable on the shaft 31, in the form of a plate having stepped surfaces 36, see Fig. 3, engageable with the cam-engaged surface of the bolt to positively hold the latter against reverse rotation at different positions within the range of bolt rotation by the cams. The structure and operation of this type of bolt holding mechanism, are more fully dealt with in my co-pending application Ser. No. 497,594 filed August 6, 1943, on Lock mechanism. Each of the cams 29 and 30, and also the step plate 35, is urged in the direction of latching rotation of the bolt by the usual individual springs

37 supported at 38 and bearing against a shoulder 39 on the cam or step plate. While only one of the springs appears in Fig. 3, it will be understood that the support 38 carries three such springs, side by side and bearing against the cam and step plate shoulders 39.

Any suitable means may be employed for manually retracting the cams and step plate from operative engagement with the bolt end 17. Merely as illustrative, the mechanism generally indicated at 44 is shown to comprise a plate 40 mounted for vertical reciprocal movement against stationary guides 41 and 42, and having an arm 43 engageable with shoulders 44 on each of the cams and step plate. The plate 40 normally is maintained in the raised position of Fig. 2 by a coil spring 44 bearing at 45 against its lower end. Plate 40 is shiftable downwardly against the resistance of spring 44 to release the cams and step plate, by either the outside handle operated roll-back 46, or the usual inside retractable link 47. The roll-back 46 comprises a rotor 48 having a square opening 49 and rotatable within openings 50 and 51 within the case flange 12 and an inside flange 52, see Fig. 3. Nose 53 on the rotor 48 is engageable with the upper turned end 54 of plate 40 to shift the latter downwardly and swing the cams and step plate to bolt releasing positions. Link 47 is pivotally connected at 55 to a lever 56 pivoted on pin 57 and having a nose 58 engageable with shoulder 59 on the plate 40, so that movement toward the right of link 47 causes the nose 58 to shift plate 40 downwardly to a cam and step plate releasing position. Pivot 57 extends through a slot 60 of sufficient length to permit shifting of the plate within the required limits of its travel.

The outer end portion 16 of the bolt is engageable with a keeper 61 which, as illustrated in Figs. 40 1, 5 and 8, is entered between the bolt and lug 34 so as to engage and advance relatively along the latter, first under manually applied door-closing force, and then under the influence of cams 29 and 30. The keeper 61 may have a flat upper surface 62 engageable with the under-face 63 of lug 34, an inclined bolt engaging surface 64, and a curved corner surface 65 receivable within the recess 28 of a bolt head, as will now appear.

Figs. 5 through 10 illustrate diagrammatically relative sequential positions of the keeper and bolt throughout the range of a complete latching operation starting with initial inter-engagement of the bolt and keeper in Fig. 5, and ending with rotation of the bolt to the home or fully latched position of Fig. 10. As will be understood, the keeper may be stationarily mounted on the usual door pillar and the bolt and associated lug carried by the door, or this relationship may be reversed. Accordingly, the described movements of the bolt and keeper are to be regarded as relative. The views of Figs. 6, 7, 9 and 10 are on a somewhat enlarged scale.

Upon movement of the bolt against the keeper beyond the position of Fig. 5, the curved corner surface 65 of the keeper is received within the recessed face 28 of the engaging bolt surface, as illustrated in Fig. 6. Continued rotation of the bolt brings the leading head 25 into engagement with the keeper surface 64 at a position reached upon just slight rotation of the bolt beyond the position of Fig. 7. For most efficient action, the operation of the cam mechanism is timed with relation to the bolt rotation, so that the cams 29 and 30 trip from their positions of

engagement with the leading face 26b of the bolt head 25b to positions of dogging or camming engagement with the trailing surface 26a, at substantially the described bolt and keeper positions of Fig. 8. In this view, the cams are shown to be at the trip position, i. e. immediately upon movement of the shorter cam into camming engagement with the bolt surface 26a. As the bolt thereafter is urged in an advancing direction by the cams, the bolt and keeper assume progressively the successive positions of Figs. 8, 9 and 10, at the last of which the mechanism is fully latched.

From the foregoing it will be understood that for most efficient action, the cam means should be caused to exert an advancing thrust against the bolt starting at substantially the point at which the leading bolt head first engages the inclined keeper surface 64, as in Fig. 8, and that the range of the cam operation should be sufficient to carry through to the home position of Fig. 10. The described bolt and keeper shapes are of importance in assuring this action to a greater extent than is possible by the use of rotary bolts having conventional shapes. Instead of curving inwardly as at 26, the corresponding surface of the usual bolt head has an outward curvature, or at least no appreciable degree of inward curvature. Now it happens that in practical installations of these locks, the relative vertical positions (as viewed in Figs. 5 through 10) of the bolt and keeper may be subject to variation from a single predetermined position on the basis of which the bolt action is designed. Such variation may result, for example, from upward bending of the lug 34, permitting corresponding upward displacement of the keeper relative to the bolt. Ordinarily, the effect would be to throw the cam action out of proper timing, as by the cams becoming tripped before the leading bolt head reaches a position of engagement with the inclined keeper surface 64, as in Fig. 8, and to cause the duration of the cam action thereafter to be insufficient to carry through to the home position in Fig. 10.

This normally encountered condition is obviated by the invention by reason of the fact that the accommodation given the corner portion 65 of the keeper within the bolt recess 28, permits substantial variation in the relative vertical positions of the keeper and bolt, without in any way seriously affecting the proper timing of the cam action. In this connection it is to be noted that at the tripping position of Fig. 8, there is sufficient vertical overlap between the keeper corner 65 and the trailing bolt head 26a, to assure rotation of the bolt to the tripping position even though misalignments may result in lowering of the bolt relative to the keeper.

The variational form of the invention illustrated in Figs. 11 to 13 represents an embodiment of a symmetrical bolt of reverse surface curvature in a latching mechanism wherein the cam means and keeper engage the same portion of the bolt, as distinguished from opposite end portions thereof. Here the latch assembly comprises a case 67 having a flange 67a at the inside of which is mounted the roll-back mechanism generally indicated at 68, and a flange 67b at the outside of which is mounted the reversible bolt 69 and its camming and holding mechanism 70. The bolt 69, shown typically as having three equi-angular heads 71 of symmetrical reverse curvature, is rotatable on its trunnion 72 supported by the case flange 67b and at 74 by the outside housing

5 15. The bolt is engageable with a keeper 76 on plate 77 which also carries a lug 78 between which and the keeper 76, the housing and bolt assembly may become confined or wedged to prevent relative vertical displacement of the locked parts.

10 Rotation of the bolt in engaging and entering the keeper is yieldably resisted and then aided by a plurality of pivoted cams 79 and 80, two being shown as typical, mounted for oscillation about a shaft or pin 81 in the case flange 67b and housing 75, respectively. The bolt engaging portion 79a of the cam 79 extends radially from the center of oscillation about pin 81 a greater distance than the bolt engaging portion 80a of element 80, so that the two elements cooperate progressively or sequentially to urge the bolt in a closing direction. The bolt engaging surfaces of the cams extend upwardly and outwardly from concentricity with the pin 81, so as to exert, upon downward swinging, a camming action against the bolt tending to turn it into and along the keeper 76. Upward swinging of the cams from the normal positions of Fig. 12 is resisted by individual coil springs 82 and 83 mounted on a suitable support 84.

15 20 25 30 35 40 Retractive rotation of the bolt within the range of its advancement by the cams is arrested by a step plate 85 also mounted for oscillation on pin 81 against the resistance of coil spring 86. Plate 85 carries an integral arm 87 projecting through an arcuate slot 88 in the case flange 67b and engaging the bottom end of the slot to limit downward swinging of the plate to the position appearing in Fig. 12. The cams have lugs 19b and 20b to limit downward swinging movement of the cams. Plate 85 has a series of stepped dogging surfaces 89, 90 and 91 at progressively increasing radial distances from the center of oscillation about pin 81, and preferably having true circular or arcuate curvature about that center.

45 As previously indicated, the structure and operation of the step plate are more fully dealt with in my copending application Ser. No. 497,594.

50 In closing the latch from a fully opened position, movement of the bolt against the end 76a of the keeper produces counter-clockwise rotation of the bolt and displacement of the cams 79 and 80 as well as the step plate 85, against the resistance of springs 82, 83 and 75 until the tripping point is reached. Thereafter the cams rotate the bolt in a latching direction with the bolt head engaged with the inclined keeper surface 76b, to the final or home position of Fig. 12.

55 60 65 70 The cam and step plate releasing mechanism is shown to comprise an outside operated roll-back having an arm 92 adapted to be operated by the door handle. Arm 92 is engageable with an arm 93 pivotally mounted on pin 94 and having a lug 93a engaged by a spring 95 resisting upward swinging movement of the arm. The arm carries a projection 96 engageable with the step plate carried arm 87 to swing the cams and step plate upwardly and together to bolt releasing positions. The cam and step plates may be released from the inside of the door by an arm 97 pivoted on pin 94 and having a projection 98 engageable with the arm 87. Arm 97 may be swung by a link connection 99 to displace arm 87 and the cams and step plate to released position.

75 The arm 97 also is operable to releasably lock the latch mechanism against release of the bolt camming and holding elements, by rendering the outside operated roll-back 92 ineffective to displace arm 97 in an upward direction to release the camming and holding elements. Upon in-

ward movement of the inside operated link 99, arm 97 is swung downward to bring a projection 98 integral therewith, in overlying engagement with a lug or projection 92a on arm 92, thus locking the latter against upward swinging movement. Arm 97 thereafter is returnable to the released position shown, either by outward movement of link 99, or by virtue of engagement of the bolt with the end of the keeper as the bolt and keeper are brought together from disengaged positions and the bolt thereupon is rotated in an advancing or rotating direction to first displace the camming and holding elements upwardly, thereby bringing arm 87 into engagement with lug 100 on arm 97 to swing the latter to the releasing position.

I claim:

1. In a latch mechanism, a rotary bolt adapted to engage a keeper, cam means for actuating the bolt, said bolt comprising a plurality of radially extending, equi-angularly spaced heads, each head having cam-engaging and keeper-engaging side surfaces, each head having at opposite sides of a radial line of the bolt, symmetrical surfaces the outer and intermediate portions of which curve respectively away from and toward said radial line so that the bolt is useable in the mechanism to the same effect in axially reversed positions.

2. In a latch mechanism, a case, a bolt carried by said case and adapted to engage a keeper, cam means for actuating the bolt, said bolt comprising a plurality of radially extending, equi-angularly spaced heads having cam-engaging and keeper-engaging side surfaces, said heads constituting integral and unitary parts of the bolt and the bolt being insertible as a unit in operating position within the case in either of axially reversed positions, the opposite side surfaces of each head having symmetrical surfaces of reverse curvature so that the bolt is operable to the same effect in said axially reversed positions.

3. In a latch mechanism, a rotary bolt having cam-engaging and keeper-engaging ends formed by a plurality of radially extending, equi-angularly spaced heads, the heads at the cam-engaging end of the bolt being offset from the heads at the keeper-engaging end of the bolt angular distances equal to one-half the angular distances between the keeper-engaging heads, and all side surfaces of all the heads having the same shape so that the bolt is useable in the mechanism to the same effect in axially reversed positions.

4. In a latch mechanism, a rotary bolt having cam-engaging and keeper-engaging ends formed by a plurality of radially extending, equi-angularly spaced heads, the heads at the cam-engaging end of the bolt being offset from the heads at the keeper-engaging end of the bolt angular distances equal to one-half the angular distances between the keeper-engaging heads, and all side surfaces of all the heads having outer and intermediate reverse curvatures of the same shape so that the bolt is useable in the mechanism to the same effect in axially reversed positions.

5. In a latch mechanism for association with a keeper having an inclined surface, a rotary bolt comprising a plurality of radially extending, equi-angularly spaced heads, each head having at one

side of a radial line of the bolt a surface engageable with the end of said keeper to cause rotation of the bolt to a position at which an adjacent bolt head is brought into engagement with said inclined surface of the keeper, and cam means for actuating the bolt and displaceable by the bolt to a tripping position, the keeper-engaging surfaces of said bolt having outer and intermediate portions which curve respectively away from and toward said radial line to form a recess receiving a corner portion of the keeper and enabling said cam means to trip substantially when said adjacent bolt head engages said inclined surface, despite variations in the spacing of the keeper and the bolt axis.

6. In a latch mechanism for association with a keeper having an inclined surface, a rotary bolt comprising a plurality of radially extending, equi-angularly spaced heads, each head having at each side of a radial line of the bolt symmetrical surfaces one of which is engageable with the end of said keeper to cause rotation of the bolt to a position at which an adjacent bolt head is brought into engagement with said inclined surface of the keeper, and cam means for actuating the bolt and displaceable by the bolt to a tripping position, said symmetrical bolt head surfaces having outer and intermediate portions which curve respectively away from and toward said radial line to form recesses for receiving a corner portion of the keeper and enabling said cam means to trip substantially when said adjacent bolt head engages said inclined surface, despite variations in the spacing of the keeper and the bolt axis.

7. In a latch mechanism for association with a keeper having an inclined surface, a case, a bolt carried by said case and adapted to engage the keeper, said bolt comprising a plurality of radially extending, equi-angularly spaced heads constituting integral and unitary parts of the bolt and the bolt being insertible as a unit in operating position within the case in either of axially reversed positions, each head having at each side of a radial line of the bolt symmetrical surfaces one of which is engageable with the end of said keeper to cause rotation of the bolt to a position at which an adjacent bolt head is brought into engagement with said inclined surface of the keeper, and cam means for actuating the bolt and displaceable by the bolt to a tripping position, said symmetrical bolt head surfaces having outer and intermediate portions which curve respectively away from and toward said radial line to form recesses for receiving a corner portion of the keeper and enabling said cam means to trip substantially when said adjacent bolt head engages said inclined surface, despite variations in the spacing of the keeper and the bolt axis.

8. In a latch mechanism, a rotary bolt having cam-engaging and keeper-engaging ends formed by a plurality of radially extending, equi-angularly spaced aligned heads, all side surfaces of all the heads having outer and intermediate reverse curvatures of the same shape.
